UNITED STATES PATENT OFFICE.

ERNEST HELLFACH, OF WALHALLA, NORTH DAKOTA.

POTATO-SORTER.

1,105,427.

Specification of Letters Patent. Patented July 28, 1914.

Application filed May 5, 1914. Serial No. 836,425.

To all whom it may concern:

Be it known that I, ERNEST HELLFACH, a citizen of the United States, and resident of Walhalla, in the county of Pembina and 5 State of North Dakota, have invented certain new and useful Improvements in Potato-Sorters, of which the following is a specification.

My invention relates to machines for sorting 10 or grading fruits and vegetables, and the main object thereof is to provide such a machine which automatically performs such operation without injury to the articles being graded, and which delivers the same at 15 different points according to grade.

A further object is to provide a grid 20 formed of longitudinally arranged bars or rods, along which the articles are carried, for grading the same.

25 A further object is to provide stationary grid bars for separating the articles into rows to assist the grading.

30 A further object is to provide supplemental grid bars, preferably arranged in pairs, beneath said first named bars, which are arranged in adjustable relationship with each other, and during the operation of the machine; and further objects are to provide such machines which are simple in construction and operation, which require no attention other than to keep the same supplied 35 with the articles to be graded and to carry the graded articles away, which are readily portable, and comparatively inexpensive.

35 My invention is fully set forth in the following specification, of which the accompanying drawings form a part, in which the separate parts are designated by the same reference characters in each of the views, 40 and in which:

Figure 1 is a front elevation of a sorting or grading machine constructed in accordance with my present invention; Fig. 2 is a similar view of the opposite side; Fig. 3 is a 45 longitudinal section taken on the line 3—3 of Fig. 4; Fig. 4 is a plan view thereof; Fig. 5 is a section taken on the line 5—5 of Fig. 1; Fig. 6 is a view of a detail; Fig. 7 is a fragmentary, perspective, view of the permanent and adjustable grid bars; Fig. 8 is 50 an enlarged, fragmentary, view of a detail

taken on the line 5—5 of Fig. 1 and on the line 8—8 of Fig. 9; and Fig. 9 is a section taken on the line 9—9 of Fig. 8.

In the drawings forming a part of this application I have shown a frame comprising side members a and a^2 and end members a^3 and a^4 , and at one end of said frame I provide a hopper a^5 formed by inclined plates a^6 and a^7 , open at the bottom, and which opening is normally closed by means of a transversely arranged, pivoted, block a^8 which is maintained in operative position by gravity, as shown, but which may also be 60 spring actuated.

65 Adjacent the end of the frame opposite the hopper is a transversely arranged power shaft b , having a sprocket b^2 thereon connected, by means of a chain b^3 , with a suitable source of power, said shaft carrying 70 also, outside of the said frame, two pulleys b^4 and b^5 connected, by means of belts b^6 and b^7 , with pulleys b^8 and b^9 .

75 The pulley b^8 is secured upon a shaft c adjacent, the top of the frame, and which carries, within said frame, two sprocket-wheels c^2 which are in connection with idler sprocket-wheels c^3 by means of chains c^4 , at opposite sides of the frame, and said chains are connected, at desired intervals, by means 80 of transverse bars c^5 which move downwardly beneath and upwardly upon the plate a^7 , the chains and bars serving as endless conveyers for any articles to be sorted and which have been placed in the hopper a^5 , and 85 I also provide idler, tension, sprocket-wheels c^6 , only one of which is shown, in Fig. 3, and, because of the block a^8 , no articles in the hopper can pass through the open end thereof, but said block is moved backwardly by 90 the bars c^5 to permit the passage thereof, the block resuming its closing position after such passage of the said bars, successively.

95 The pulley b^9 is secured to a shaft d which also carries, within the frame, sprocket-wheels d^2 , only one of which is shown, in Fig. 3, connected, by means of chains d^3 with idler sprockets d^4 on a shaft d^5 , the shafts d and d^5 also having rollers d^6 and d^7 thereon for endless, fabric, conveyer belt d^8 movable 100 above and below a supporting plate d^9 .

The shaft b carries, within the frame,

sprocket-wheels e^2 connected, by chains e^2 , with idler sprockets e^3 , e^4 and e^5 , these being clearly shown in Fig. 3, arranged in approximately a rectangle, the sprockets e^4 and e^5 being below and in line with the shaft e , and said chains are connected by means of transverse bars e^6 having, each, a plurality of inwardly directed fingers e^7 secured thereto, the detail construction of the chain and 10 bar connection being shown enlarged in Figs. 8 and 9, wherein is shown a plate e^8 connecting each bar with the corresponding link of the chain and, in the position of each bar e^6 , outside of the chains, are guides e^9 which move in grooves in the side members a and a^2 of the frame for a reason later pointed out, and it will be seen that the chains e^2 move over and beneath the conveyer belt d^8 .

20 Arranged transversely beneath the idlers e^4 is a chute formed of a bottom and two side members, f , f^2 and f^3 , respectively, and at each end of said chute, one within and the other outside of the frame, are longitudinally arranged shafts f^4 and f^5 , each of which carries sprockets f^6 and f^7 , respectively, for chains f^8 and f^9 , and between which is an endless conveyer belt f^{10} which rests on the bottom f of the said chute, the 30 sprockets on the shaft f^5 being idlers whereas those on the shaft f^4 are power driven, as will be described.

As clearly shown in Figs. 1 and 4, the shaft f^4 is arranged outside of the side member a of the frame, and extends to the position of a transverse shaft h and is connected therewith by means of bevel gears h^2 and h^3 , said shaft carrying, within the frame, a sprocket h^4 which is geared to a 40 sprocket h^5 on the shaft h^6 which carries the idler e^3 by means of a chain h^7 , and it will be seen that the shaft f^4 is thus rotated by the power shaft b and thereby actuates the conveyer belt f^{10} during the movement of the 45 chains e^2 and of the conveyer belt d^8 .

To the rear of the conveyer belt d^8 is arranged a chute i , formed of bottom, and side members i^2 , i^3 , and i^4 , respectively, sprockets i^5 and i^6 being secured to the shaft 50 i^7 , and connected with suitable sprockets, not shown, by means of chains i^7 and i^8 , which are in turn connected by means of a conveyer belt i^9 moving over the bottom member i^2 of the chute i , and it will thus be seen 55 that this conveyer belt is also moved with those already referred to, the conveyer belts f^{10} and i^9 passing through the front member a of the frame to deliver the sorted articles at different points.

60 Transversely arranged on the members f^2 and i^2 of the chutes just described are members k carrying uprights k^2 which support longitudinally arranged, stationary, grid bars k^3 suitably spaced, these being clearly

illustrated in Fig. 7, and slidably arranged 65 in the said uprights are two bars k^4 and k^5 , above each of the members f^2 and i^2 , said 70 slidable bars having uprights k^6 and k^7 , respectively, and between the uprights k^6 of the two sliding bars k^4 are arranged grid bars k^8 , whereas between the uprights k^7 of the two sliding bars k^5 are arranged grid bars k^9 , said bars being beneath the grid bars k^8 , and said last named grid bars are 75 directly under and serve to support the 80 transverse bars e^6 of the endless chains e^2 , this being clearly shown in Fig. 3; the sliding bars k^4 are each provided, at their forward ends, with a rack l in the same horizontal plane as the bars, while the bars k^5 have, each, a rack l^2 arranged in a higher plane than the racks l , as shown in Figs. 5 and 7, said racks being in engagement with corresponding pinions l^3 , only one being 85 shown in Figs. 5 and 7, but clearly shown in 90 duplicate in Fig. 4, arranged on a shaft l^4 rotatable in suitable brackets l^5 on the outer face of the member a of the frame, and said shaft l^4 has a lever l^6 secured thereto and whereby it may be rotated. When the lever 95 is turned, through an arc of a circle, the pinions l^3 are revolved, thus moving the sliding bars k^4 outwardly and the bars k^5 inwardly when the lever is moved upwardly, and reversing this movement of the sliding 100 bars when the lever is moved downwardly, in the first movement carrying the grid bars k^8 and k^9 toward each other, and in the second direction of movement moving the said grid bars away from each other, and a desired spacing of the said grid bars thus results and limits the size of the articles to be sorted which may pass between said grid bars and to the conveyer belt d^8 , thence to the conveyer belt f^{10} and outwardly of the 105 frame to a suitable basket or other receiver.

The fruit or vegetables to be sorted are dumped into the hopper a^5 , whence they are removed by the bars e^6 on the chains e^2 and carried upwardly until they fall upon the 110 grid formed of the bars k^8 , k^8 and k^9 , the bars k^8 forcing the said articles into rows occupied by pairs of the bars k^8 and k^9 , and the bars e^6 on the chains e^2 carry the articles along the grid bars, the fingers e^7 projecting 115 downwardly between said grid bars to insure the continuous movement of the articles, and such articles as may, because of the small size thereof, pass between the grid bars k^8 and k^9 to the conveyer belt d^8 and outwardly, as just described, but the articles of larger size are carried along the grid bars until they fall upon the conveyer belt i^9 whence they are carried outwardly of the 120 machine to another delivery point, the grid bars terminating at the near side of the chute i , as will be seen, and the articles are thus graded or sorted into two sizes in the 125

machine shown, but the delivery points and conveyer belts thereto may be increased in number, as will be understood, as may also the number of sets of the adjustable grid 5 bars.

If it is desired to sort very small articles, the lever l^6 is moved upwardly to cause the grid bars h^8 and h^9 to approach each other, or the lever is moved downwardly to move 10 the said grid bars apart and thus produce less distinction between the sorted articles at the different delivery points, this adjustment being possible in the operation of the machine.

15 My invention therefore consists of a frame provided with a hopper to receive the articles to be sorted, conveyers to carry the articles to different points of delivery according to size, and means intermediate the 20 hopper and points of delivery for sorting the articles, which sorting means are readily adjustable by merely moving a lever during the operation of the machine and, while I have shown specific means for accomplishing 25 the desired result, it will be obvious that various changes thereover may be made, within the scope of the following claims, without departing from the spirit of my invention or sacrificing its advantages.

30 Having fully described my invention, what I claim as new, and desire to secure by Letters Patent, is:—

1. An assorting machine, comprising a frame provided with a hopper and a plurality 35 of delivery points, conveyer means from said hopper to the individual delivery points, stationary, longitudinally arranged, grid bars suitably spaced, and adjustable grid bars arranged between said stationary 40 grid bars in pairs, and means for adjusting said pairs of bars, said grid bars being arranged intermediate said hopper and said delivery points.

2. An assorting machine, comprising a 45 frame provided with a hopper and a plurality of delivery points, a grid consisting of a plurality of stationary bars and a plurality of movable bars arranged in pairs therebetween, means for adjusting the bars 50 of each pair toward or from each other, conveyer means to said grid, and conveyer means from said grid to said delivery point.

3. An assorting machine, comprising a 55 frame provided with a hopper and a plurality of delivery points, a grid consisting of a plurality of stationary bars and a plurality of movable bars arranged in pairs therebetween, means for adjusting the bars 60 of each pair toward or from each other, conveyer means to said grid, conveyer means along said grid, and conveyer means from said grid to each of said delivery points.

4. An assorting machine, comprising a 65 frame provided with a hopper and a plurality of delivery points, a grid consisting of a plurality of stationary bars and a plurality of movable bars arranged in pairs therebetween, means for adjusting the bars 70 of each pair toward or from each other, conveyer means to said grid, conveyer means along said grid provided with fingers extending between each pair of said movable bars, and conveyer means to each of said delivery points from said grid.

5. An assorting machine comprising a 75 frame provided with a hopper and a plurality of delivery points, a grid consisting of a plurality of stationary bars and a plurality of movable bars arranged in pairs therebetween, a rack connected with one of 80 each pair of movable bars, a supplemental rack connected with the other of each pair of movable bars, a pinion in engagement with said racks, means for actuating said pinion to move said racks and thereby 85 said movable bars of each pair toward or from each other, conveyer means to said grid, conveyer means along said grid, and conveyer means from said grid to each of 90 said delivery points.

6. An assorting machine, comprising a frame provided with a hopper and a plurality of delivery points, a grid consisting of a plurality of stationary bars and a plurality of movable bars arranged in pairs 95 therebetween, a rack connected with one of each pair of movable bars, a supplemental rack connected with the other of each pair of movable bars, said racks being duplicated at each end of said movable bars, pinions 100 in engagement with corresponding racks, a shaft for both of said pinions, a lever for rotating said shaft to move the bars of each pair toward or from each other, conveyer means to said grid, conveyer means along 105 said grid, and conveyer means from said grid to each of said delivery points.

7. An assorting machine, comprising a frame provided with a hopper and a plurality of delivery points, a grid consisting 110 of a plurality of stationary bars and a plurality of movable bars arranged in pairs therebetween, means for adjusting the bars of each pair toward or from each other simultaneously, conveyer means from said 115 hopper to said grid, conveyer means along said grid, conveyer means from said grid to each of said delivery points, and means for actuating said conveyers in unison.

8. An assorting machine, comprising a 120 frame provided with a hopper and a plurality of delivery points, a grid consisting of a plurality of stationary bars and a plurality of movable bars arranged in pairs therebetween, means for adjusting the bars 125 of each pair toward or from each other simultaneously, conveyer means from said hopper to said grid, conveyer means along

said grid, guides on said last named conveyer means, said frame being provided with grooves for said guides, conveyer means from said grid to each of said delivery points, and means for actuating said conveyer means in unison.

In testimony that I claim the foregoing

as my invention I have signed my name in presence of the subscribing witnesses.

ERNEST HELLFACH.
